Primary Examiner — Sandra Snapp(74) *Attorney, Agent, or Firm* — Taft Stettinius & Hollister LLP(57) **CLAIM**

The ornamental design for a watch dial, as shown and described.

DESCRIPTION

FIG. 1 is a front side view of a watch dial of the present invention.

FIG. 2 is a rear side view of the watch dial of FIG. 1.

FIG. 3 is a right side view of the watch dial of FIG. 1.

FIG. 4 is a left side view of the watch dial of FIG. 1.

FIG. 5 is a bottom side view of the watch dial of FIG. 1.

FIG. 6 is a top side view of the watch dial of FIG. 1.

FIG. 7 is a front-side perspective view of the watch dial of FIG. 1; and,

FIG. 8 is a rear-side perspective view of the watch dial of FIG. 1.

The broken lines in the drawings are used to show portions of the watch dial that do not form part of the claimed design.

1 Claim, 4 Drawing Sheets(56)
